UNITED STATES PATENT OFFICE

2,681,256

ENSILAGE DISTRIBUTOR

Victor J. Knoff, Ivanhoe, Minn.

Application July 5, 1951, Serial No. 235,197

1 Claim. (CL 302—60)

1 This invention relates to new and useful improvements and structural refinements in ensilage distributors of the type which are used for uniformly distributing grain or other material into a bin, or the like, and particularly, this invention relates to certain improvements in the distributor which forms the subject matter of my Patent No. 2,557,977, issued on June 26, 1951.

The primary object of the instant invention is to provide novel means for rotatably mounting the distributor on the discharge end of an ensilage delivery conduit, the mounting means being such as to facilitate easy rotation of the distributor in response to material flowing from the delivery conduit and impinging against the distributor vanes.

Some of the advantages of the invention reside in its simplicity of construction, in its durability, in its efficiency of operation and in its adaptability to economical manufacture.

With the above more important objects and features in view and such other objects and features as may become apparent as this specification proceeds, the invention consists essentially of the construction and arrangement of parts as shown in the accompanying drawings in which:

Figure 1 is a side elevational view of the invention mounted at the discharge end of ensilage delivery conduit;

Figure 2 is a top plan view thereof; and,

Figure 3 is a fragmentary sectional detail, taken substantially on the plane of the line 3—3 of Figure 2.

Like characters of reference are employed to designate like parts in the specification and throughout the several views:

Referring now to the accompanying drawings in detail, the general reference character 10 designates an ensilage delivery conduit which has a downturned discharge end 12, the ensilage distributor being designated generally by the reference character 14.

An annular supporting member or ring 16 is provided with an arcuate bail 18 whereby it is suspended from a hook 20 at the lower end of the downturned discharge end or spout 12, and in addition, the supporting member 16 is also rigidly secured to the conduit portion 12 by a pair of straps or brackets 22.

A plurality of radial, inwardly projecting studs 24 are secured to the support member 16 by pairs of nuts 26, each of the studs 24 carrying a pair of anti-friction bearings 28 to support a roller 30. The bearings 28 are sustained in position on the studs 24 by an additional nut 32 (see Figure 55).

2 3) and the several rollers 30 engage a circumferential track 34 provided in an annular race 36. The race 36 is rigidly secured by suitable rivets, or the like, 38 to the upper end of a substantially tubular casing 40, whereby this casing, together with the race 36, may freely rotate on the rollers 30 relative to the stationary supporting member 16.

The lower end of the casing 40 has secured thereto as at 42 a laterally projecting discharge spout 44, and a plurality of arcuate propelling vanes 46 are mounted on the inner surface of the casing 40, whereby the casing, together with the spout 44, are rapidly rotated in response to material flowing from the discharge end 12 and impinging against the blade or vanes 44. Needless to say, by virtue of this rotation, the casing 40 and the discharge spout 44 will properly and evenly distribute the material in a bin, or the like.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

In an ensilage distributor, the combination of a stationary annular supporting member, a set of inwardly projecting radial studs secured at circumferentially spaced points to said member, a set of rotatable anti-friction elements mounted on the respective studs within said member, an annular race disposed coaxially within said member and provided in its outer circumferential edge with an annular channel having said anti-friction elements disposed therein whereby the race is rotatably supported, and a distributor casing depending from said race and fitted and secured therein.
